UNITED STATES PATENT OFFICE.

WILSON BARR, JR., OF HAMILTON, ONTARIO, CANADA.

ACCOUNT-FILE.

1,107,742.

Specification of Letters Patent. Patented Aug. 18, 1914.

Application filed October 23, 1912. Serial No. 727,439.

To all whom it may concern:

Be it known that I, WILSON BARR, Jr., of the city of Hamilton, in the Province of Ontario, Canada, have invented certain new and useful Improvements in Account-Files, of which the following is a specification.

This invention relates to improvements in account files of the type in which a series of frames hinged together in the form of a book are supported in a casing so that they may be turned up or down to expose either side of each leaf, and my object is to devise a construction which will result in the top leaf of those which may at any time be in the down position lying in substantially the same horizontal plane no matter how many of the leaves may be up or down.

In such a construction it is particularly my object to provide simple means for resiliently supporting the leaves when down and means for relieving the hinges of the leaves when up from strains due to the upward pressure of said supporting means.

It is also my object to devise a form of hinge construction for the leaves which will enable the leaves to be reduced in thickness to the minimum allowable having in consideration the provision of sufficient bill holding capacity and to provide a simple and convenient index.

I attain my objects by providing each hinge of the book of leaves with projecting pins. The rear leaf is pivoted on the casing and the pins of the intermediate leaves engage beneath guide bars, preferably pivoted and releasably locked so that they may be swung up out of the way when it is desired to remove the book of leaves.

A substantially horizontal table is provided on which the leaves are supported when down, which table is carried by parallel pivoted links spring actuated to resiliently support the table. The rims of the leaves are in T-form being made of sheet metal folded to shape and embracing the plate forming the body of the leaf. Sheet metal hinge members are provided with hinge knuckles and are riveted to the flanges of the lower rims of the leaves. Each hinge member has an end flange formed thereon turned up to fit against the side rim of the leaf and riveted thereto.

The index comprises a series of substan-

tially vertical leaves hinged "en echelon" and provided with springs engaging one or more hinges and tending to retain the leaves in their normal positions, all substantially as hereinafter described and illustrated in the accompanying drawings in which—

Figure 1 is a side elevation of my improved register, the casing being shown in section; Fig. 2 is a plan view of the same, the casing also being shown in section; Fig. 3 is a detail in side elevation of part of the device showing one of the guide bars swung up. Fig. 4 a front view of the index. Fig. 5 a vertical section of the same. Fig. 6 an end elevation showing the hinges of two leaves. Fig. 7 a section of the same. Fig. 8 a perspective view of the same; and Fig. 9 a plan view of a single hinge and part of a leaf.

In the drawings like numerals of reference indicate corresponding parts in the different figures.

1 is the casing suitably shaped to support the different parts.

2 are the bill holding leaves connected together by the hinges 3 in the form of a book. To the last leaf are secured the pivot pins 4 which engage in open bearings formed in the bearing brackets 5 secured to the back of the casing. The leaves are supported on the table 6, the first leaf of the book being preferably provided with an anti-friction roller adapted to rest on the table. The table is carried by the parallel links 8 pivoted at the bottom of the casing and to the under side of the table. These links maintain the table in a substantially horizontal position as it is raised or lowered.

Resilient means are provided tending to raise the table. For this purpose I prefer to employ the coil springs 9 wound on the spindles 10 which form the journals of the links 8 and are journaled in the lugs 11. These coil springs have their ends secured respectively to the casing and the spindles and are constantly in tension.

Upward pressure of the table tends to bring a strain on the hinges of those leaves which are in a substantially vertical position. If this strain were not relieved the tendency would be to force up the front leaves beyond their proper position and ultimately to break the hinges. To resist

this tendency I provide the guide bars 12 which are preferably pivoted on the bearing brackets 5 in such a position that when down they close the open bearings in the brackets 5 as shown in Fig. 1 and when up leave the same open to permit of the pivots 4 being lifted out of their bearings when it is desired to remove the book from the apparatus. The guide bars are normally 10 locked down by means of the pivoted latches 13 which, however, may be thrown back as indicated in Fig. 3 to release the guide bars. The hinges between the leaves are provided with the projecting pins 14 which engage 15 the under sides of the guide bars as shown and thus serve to take the strain due to the upward pressure of the table 6.

From the construction described it will be seen that one or more leaves may be readily 20 turned down from their up position to the down position or vice versa to expose either side of any given leaf and that the up leaves will all be substantially vertical and the down leaves substantially horizontal. It 25 will be seen also that the spring actuated table perfectly supports and balances all the leaves whether vertical or horizontal.

Each leaf is formed of a sheet of metal 15 and its rims 16 are formed of sheet metal 30 doubled and bent to T-form, embracing the edges of the sheet 15 and riveted or otherwise secured thereto. The hinge members 17 are also formed of sheet metal and the hinge knuckles 18 are integral therewith. 35 The inner end of each hinge member 17 extends inwardly beyond the knuckles and is secured to the flanges of the bottom rim member 16 by means of the rivets 19. As the outer hinge knuckle 18 must come close 40 to the side rim of the leaf to support the projecting pins 14, there is no room to rivet the hinge member adjacent the said edge. I therefore form the flange 20 integral with each hinge member and turn it up against 45 the side rim member 16 to which it is secured by means of the rivets 21 passing through the flanges thereof. This arrangement gives a very neat, light, strong and comparatively cheap hinge construction.

50 The index comprises a series of leaves 22 secured to hinge rods 23 pivoted in the inclined bars 24 secured to the casing of the apparatus so that the index leaves when in normal vertical position are arranged "*en echelon*". One or more of the hinge rods 23 are provided with coil springs 24 secured at one end to the leaf or rod and at the other to some stationary part. About every 55 fourth leaf is preferably so equipped and the result is that the leaves are normally yieldingly pressed toward the upright position and an equable counterbalance provided for the leaves as drawn down to expose any given leaf. A rod 25 serves as a 60 back stop to limit the rearward movement

65 of the last leaf and thus of the others as well. This index is thus out of the way, is not exposed except when in use and then only to a limited extent, and yet is quickly and easily accessible when needed.

70 What I claim as my invention is:—

75 1. In an account file the combination of a casing; a plurality of bill-holder leaves hinged together so that they may be turned to substantially vertical or horizontal positions; a pivotal connection between the rear leaf and the casing; a resiliently supported vertically movable table on which the leaves are supported; and a guide bar at each side of the casing, parts on said leaves being 80 adapted to engage beneath said guide bars.

85 2. In an account file the combination of a casing; a plurality of bill-holder leaves hinged together so that they may be turned to substantially vertical or horizontal positions; a pivotal connection between the rear leaf and the casing; a resiliently supported vertically movable table on which the leaves are supported; a guide bar at each side of the casing; and pins projecting from the 90 hinges of the leaves adapted to engage beneath said guide bars.

95 3. In an account file the combination of a casing; a plurality of bill-holder leaves hinged together so that they may be turned to substantially vertical or horizontal positions; a pivotal connection between the rear leaf and the casing; a resiliently supported vertically movable table on which the leaves are supported; a guide bar pivoted at each 100 side of the casing; latches for locking said guide bars down in position, parts on said leaves being adapted to engage beneath said guide bars.

105 4. In an account file the combination of a casing; a plurality of bill-holder leaves hinged together so that they may be turned to substantially vertical or horizontal positions; pivots on the rear leaf; open bearings for said pivots on the casing; a guide bar 110 at each side of the casing pivoted so as to be movable to open or close said bearings; a resiliently supported vertically movable table on which the leaves are supported; and pins projecting from the hinges of the 115 leaves adapted to engage beneath said guide bars.

120 5. In an account file the combination of a casing; a plurality of bill-holder leaves hinged together so that they may be turned to substantially vertical or horizontal positions; a pivotal connection between the rear leaf and the casing; a substantially horizontal table on which said leaves are supported; links acting between said table and the casing whereby the table is movable vertically while remaining substantially horizontal; and springs tending to lift said table.

125 6. In an account file the combination of a casing; a plurality of bill-holder leaves 130

hinged together so that they may be turned to substantially vertical or horizontal positions; a pivotal connection between the rear leaf and the casing; a substantially horizontal table on which said leaves are supported; parallel links pivoted to said table and secured to spindles journaled in the bottom of the casing; and coil springs wound

on the spindles and engaging said spindles and the casing to tend to lift said table. 10
Trenton, Ont., this 15th day of October, 1912.
